Application September 24, 1956, Serial No. 611,501

5 Claims. (Cl. 240—81)

This invention relates to a lamp having a leaning light transmissive pedestal supporting a light source thereabove, offset from the center of a base on which it is mounted. Such lamp may be used as an ordinary lamp for vertical illumination, or as a "so called" torch lamp, usually without substantial interference beneath the upper light by the pedestal. More particularly the leaning, obliquely ascending pedestal portion for lamp support, itself comprises a light transmissive housing providing lateral illumination, preferably from at least one fluorescent tube as a light source therein.

Thus the lamp hereof provides vertical illumination from a light source above the pedestal, generally free from interference by the leaning pedestal, and lateral illumination from at least some of the light transmissive sides of the pedestal from the light source, preferably one or more elongated fluorescent tubes, within the pedestal, thereby providing a lamp of great attractiveness and improved utility for illumination.

As the terms are used herein the words "leaning pedestal" or "obliquely mounted pedestal" are intended to refer to a pedestal extending upward from a base inclined thereto at an oblique angle of about 5 to 45°, usually inclined to the vertical about 10 to 30°, a sufficient angle to support a light source such as a bulb and shade above the top of the pedestal and offset from the center of a large base portion, and sometimes at a point outside of a vertical line upward from the lamp base.

According to the present invention, a lamp is provided having a substantially elongated hollow pedestal portion extending upward from a base, but leaning angularly from the vertical. The pedestal preferably is substantially enlarged in horizontal section to house one or more elongated sources of light, such as elongated fluorescent tubes, preferably mounted obliquely, usually parallel to the inclination of the pedestal in which each is housed. The pedestal preferably supports above its upper end a conventional light source, such as a bulb and shade. For optimum balance, to stably support the upper light source, a substantial distance above the base, to comprise either a floor or table lamp, the pedestal preferably is substantially wider at the lower base portion end, tapering to the top. In a modification, for purposes of housing more than one elongated fluorescent tube, the pedestal may be formed as two columnar housings, a lower column and an upper column, one being laterally offset from the other at an intermediate portion for optimum stable balance upon the base, to have an inclined or leaning pedestal effect.

For optimum laterally directed illumination, the pedestal may be shaped as an inclined pyramid, truncated at the top, of any useful number of sides but preferably rectangular, as shown in the drawings. That tapered or pyramidal construction as shown in Figs. 1 and 2 tends to concentrate the weight of the pedestal portion below the mid portion for greater lamp stability. However, in the modification of Figs. 3 and 4, substantial

2

stability together with certain other advantages are available by lateral off-setting of two housings, one above the other.

The rectangular, leaning or inclined hollow pedestal, as shown in the drawings, is formed at least in substantial portion of light transmissive solid materials, most of which may be light translucent, but preferably some portion such as two of the four sides of the pedestal is either light transparent, or has a greater light transmissivity than other portions of the pedestal. Such construction, transmits more concentrated illumination by light beams in certain lateral directions, while reducing glaring, and supplying softer light through the less light transmissive pedestal portions.

Great advantages are available in a leaning pedestal lamp of this character in that maximum utility results from an elongated pedestal portion to support a floor or table lamp thereabove, using such lamp in a versatile manner to illuminate objects over which the lamp "leans" as well as the ceiling, like a torch lamp; and also or independently using the pedestal portion as an important lateral source of light. Thus the pedestal portion is a useful light source to supply lateral light, sometimes at intermediate heights of a non-glaring character. With the leaning pedestal, moreover, the lamp can be positioned close to one seated on a chair or at a desk working position for use thereof using vertical and horizontal light without directing glaring light horizontally into the eyes of the user of such lamp. Again that leaning pedestal effect allows such lamp usefully to be mounted in a corner position both as a torch lamp to light the ceiling and direct light directly downward, and for total lateral lighting of converging walls of the corner. The leaning effect of the pedestal allows mounting of either a shelf upon which objects may be placed for attractive illumination thereof, or the mounting of flowers in a pot at an intermediate portion of such pedestal. Where such shelf or flowers are omitted, that intermediate portion may be occupied by a desk or working table on which the lamp may be mounted close for intermediate lateral and vertical illumination.

Other features and advantages of a lamp constructed according to this invention will be inherent in the ensuing description which is made with reference to drawings in which,

Fig. 1 is a side view of a leaning pedestal lamp in elevation with parts broken away to show internal construction,

Fig. 2 is a rear view of the lamp of Fig. 1 illustrating a removable panel upon which a fluorescent tube may be mounted for support and replacement,

Fig. 3 is a side view in elevation of a modified leaning pedestal lamp in which two laterally offset pedestal housings are mounted together as a single leaning pedestal, each housing a fluorescent light,

Fig. 4 is a front view of the lamp of Fig. 3,

Fig. 5 is a detailed view of the panel of Fig. 1 showing assembly of a fluorescent tube thereto,

Fig. 6 is a wiring diagram for a single fluorescent tube combined in a lamp as shown in Fig. 1, and

Fig. 7 is a detail showing laminated light transmissive panel construction.

As shown in Fig. 1 a hollow base 10 comprising vertical leg panels 12 joined in a quadralateral surmounted by horizontal plate 14 has mounted thereon a leaning pedestal 16. That base and leaning pedestal is formed in large part if not entirely of light transmissive sheet paneling, usually of plastic, secured together in the form of a leaning rectangular pyramid by adhesion or fusion of thermoplastic paneling pieces. The leaning pyramid is truncated at the top and supports a panel piece 18, the entire pyramid being supported upon a horizontal

panel piece 20 at the leaning pedestal bottom ornamenteally secured in leaning position for optimum stability from about the rear edge of the base panel or plate 14.

The leaning pyramidal rectangular pedestal construction comprises an assembly of four panels, that is, two end panels, one at the rear 22 and another at the front 24 each comprising narrow strips, usually but not necessarily of the same width, and two side panels, 26 at the front side (in this view partly broken away to show internal construction) and 28, at the opposite rear side. The side panels 26 and 28 are secured to the end panels 22 and 24 by reenforcing marginal strips 30 and 32 at each side as well as 34 at the bottom.

As indicated, all of the pedestal paneling may be formed of light transmissive plastic. It is preferred that at least the front and side panels 24, 26 and 28 of the lamp be the light transmissive, but these panels, to avoid lateral glare and visibility of internal construction may each be light translucent rather than transparent. Thus the internal construction and mounting of fluorescent lamps within the leaning pedestal may not be directly observed. However, it is further preferred that the side panels 26 and 28 have a greater light transmissivity than the forward panel 24 for direction of more intense illumination from these two opposite sides. The forward panel 24, together with vertical reenforcing strips 30 and 34 may have the same low degree of light transmissivity, and have a substantially lower light transmissivity than the side panels 26 and 28. The advantage of this is that most of the distribution of light non-glaringly but of higher intensity for illumination will take place through the side panels 26 and 28, having the higher light transmissivity, yet such light is diffused sufficient to be non-glaring, thereby allowing great lateral but very useful illumination of the lamp from the pedestal. The lamp may be placed upon a table as a table lamp, or close to a table or desk. The forward panel 24 desirably shields the forward end from large light transmissivity, yet provides considerable lateral illumination, whereby the lamp pedestal provides useful lateral illumination while shielding the front end from high intensity light passed directly forward to effect this lateral variation in light intensity. The rear panel 22 may have even less light transmissivity to prevent shadows of internal elements from becoming visible, and for that purpose may even be opaque.

The panels 26 and 28 may be formed of light transmissive sheet material such as plastic sheet, which may be any of the plastic film substances. As shown in detail Fig. 7, the sheet paneling may have embedded therein fiberous materials of various plastic types, preferably fiber glass which greatly reenforces such thin film. That thin light transmissive film comprising panels 26 and 28 may also be formed of parchment, glazed paper or including glassine, which has reinforcing fibers embedded therein. However, it is preferred to use, for additional reenforcement, a laminate of two or more thin films adhered together, each having fiber embedded in the film, using a transparent adhesive coated as an adhesive layer for bonding the thin films together as a laminate.

As illustrated in the detail Fig. 7, the laminate comprises an upper sheet 36 adhered to a lower sheet 38 by an intermediate layer of adhesive 40. Fiber glass or other reinforcing fiber 42 is distributed in the sheet material and the adhesive. The fiber serves to reduce the natural transparent character of the film and adhesive substances to the desired degree.

The paneling 22 and 24 as well as reenforcing strips 30 and 34 may be formed of acrylic resin of relatively heavy gage for supporting the stresses required in this lamp construction, such being available under the trade name Plexiglass. Other plastic materials, such as styrene and styrene modified polyester resins may be used for this purpose.

Secured for support to the pedestal above the panel 18 is a light bulb and shade supporting socket 44 in which a bulb 46 is threaded and supporting thereabout a glass shade 48 for directing unshaded light upward, as in a torch lamp, and diffuse light directly downward. The socket 44 has a conventional electric switch for control of current to bulb 46, operated by a knob 50.

In the construction as shown in Fig. 1, the rear panel 22 is removably fastened to the pedestal by screws 53 to cross braces 52 which may likewise be formed of plastic secured laterally to the reenforcing strips 30. The panel 22, entirely removable by unfastening the screws 53 from the cross braces 52, has mounted thereto a long fluorescent lamp tube 54. Fluorescent tube 54 is secured at opposite ends in conventional fluorescent tube contact supports 56 which both support the tube securely and removably against the panel 22, but further support electrical wiring leads and switches 58 and 60 against that panel 22 for circuit control of current to fluorescent tube 54. Removable panel 22 thereby supports lateral lighting the entire assembly, comprising the fluorescent tube 54 and current regulating and wiring means, including a starter 70 and sometimes a ballast 66, all secured to the panel 22, so that the entire assembly may be removed from the lamp pedestal for replacement of the fluorescent tube and repairs to the wiring when needed.

If desired, another hand operated switch 60 may be mounted on the panel 22 for control of the total input circuit both to the lateral lighting tube 54 as well as the vertical light 46. Thus three switches are provided, a switch 50 for control of current to the upper light bulb 46, a switch 58 for control of current to the fluorescent tube 54 in the pedestal, and a control switch 60 for control of both whereby a single switch position may operate both lights or either the upper light 46 by actuation of switch 50, or the fluorescent lamp 54 by actuation of switch 58 may be independently lighted. Thus the lateral fluorescent light may be the primary choice of light, or the upper light bulb 46 maybe the primary source of light, or both may be used in combination in most usual use.

The actual wiring of this lamp is shown in detail in Fig. 6. A conventional plug inlet 62 having a switch 60 in its circuit may pass current directly to lamp bulb 46, individually controlled by a switch 50. An independent circuit taking current from the main circuit thru lines 64 and passes current to one lead of a ballast 66 and thence to one contact 67 of the fluorescent lamp bulb 54. Two other opposite ends of the tube 54 are interconnected through contacts 68 by way of a starter 70 of conventional construction. The fourth lead 72 of the fluorescent tube is connected to the other main circuit input line 74 by way of switch 58 for independent actuation of the fluorescent light circuit. As shown in the dotted line position Fig. 1, the ballast 66 may be mounted in the hollow lamp base 10, that lamp base being sufficiently opaque, so that the ballast element is not visible. However, it may be mounted against the panel 22, if desired.

It will be seen that in Fig. 1 the fluorescent tube 54 is a single readily replaceable tube, by removal of the panel 22 extending almost from one end to the other and parallel thereto in the inclined position thereof. In that position, most of the weight of the tube 54 and the operating units at the bottom are below the center of the pedestal tending thereby to balance the lamp on the base, since the pedestal is mounted from the rear thereof to readily distribute the weight for greater lamp stability. This weight distribution tends to offset the upper lamp portion 48 so that the upper source of illumination desirably falls outside of the center of the base, but the lamp structure, notwithstanding has good stability.

The lamp of Fig. 1, due to the inclination of the

pedestal, is well adapted for placing close to a desk from the floor, or upon a desk as a table lamp, for use of the light available from both sources i. e., from the pedestal portion directed laterally of the highly light transmissive paneling, including some illumination from the forward translucent portion 24, and from the upper lamp portion from bulb 46 which supplies light downward upon such table or desk. For other uses, it is sometimes desirable to mount shelf portion 76 from any intermediate height of the lamp which serves the purpose of a support for objects to be illuminated. That shelf portion 76 may be reenforced for support by vertical paneling 78, including a web 80 of decorative character, shown here as having corrugations. The panel 78 may be divided and flared into a receptacle 82 for further support of the shelf 76 or, omitting the shelf 76, that receptacle 82 may receive flowers to enhance the decorative effect, as shown in Fig. 3. Moreover, as shown in Fig. 3, the translucent shade 48 may further have a conventional lamp shade 84 mounted thereabout for directing and shading of light, except light in the vertical direction, including downward upon such shelf mounted object, or flowers.

In another embodiment of this invention, as shown in Fig. 3 and Fig. 4, the inclined pedestal comprises a single inclined central shaft 86 extending from the base to the upper light source. That shaft 86 has a single panel 88 closing a hollow rectangular interior and is removably secured thereto by screws 90. Adjacent to the rear side of the upper end, a rectangular pyramid 92 rises from about the vertical midpoint of the leaning pedestal shaft 86, and is enclosed at the bottom and ends by translucent paneling 96 of the type shown in Fig. 7, thus to form a pyramidal housing to the upper rear of the leaning pedestal shaft 86. A similar, but inverted housing portion 98 begins near the bottom of the upper housing portion, shaped as an inverted pyramid disposed below the upper pyramid on the forward or front side of the pedestal shaft 86, continuing from the midpoint down to about the bottom plate 20. Since the leaning pedestal shaft 86 of itself substantially supports both upper and lower pyramidal housings, the forward lower pyramidal housing 98 to the right side of the shaft 86 of Fig. 3 may have an inverse taper, being wider at the top than at the bottom.

The pedestal shaft 86 is reenforced by sheet paneling 100 at the rear as a bracket support therefor in its inclined vertical position from the base 10 and further reinforced at the forward end by the adjacent narrower lower housing portion of the lower housing 98. Thus two pyramidal housings are mounted on either side of a single leaning pedestal shaft 86, and one or preferably both of these housings have mounted therein a fluorescent tube 54a and 54b, each may, as desired, be independently controlled by light switches 58 and 59. According to this construction, strong lateral illumination is provided through side panels 96 (or 26 as in the construction of Figs. 1 and 2), while providing independent light sources in both lower and upper housings comprising the pedestal. In this modification, each tube may be separately replaced by removing of the single panel 88. Great attractiveness and utility is provided in a lamp of this modified type by being able independently to illuminate either the lower half of the pedestal or the upper half of the pedestal from independent current controlling switches 58 and 59 or if, desired, both lamps may be controlled from a single switch 60 as shown in Fig. 1.

The upper end of the lower housing 98 forms a space upon which a shelf 76 may be mounted as in Fig. 1 for optimum illumination, both laterally and vertically of objects placed thereon; or, for improved attractiveness, the upper portion of that lower housing may comprise a hollow pot 82 as a base for flowers or other ornamental objects attractively illuminated in this manner. It is possible, particularly, where the leaning pedestal is greatly elongated such as for floor lamp use, to omit the light

source in the lower pedestal portion whereby only the upper housing provides lateral illumination. It is also possible, since end panels 94, 22 or 24 desirably have decreased light transmissivity, that they have high light reflectivity, even mirror-like light reflective surfaces.

There are many advantages to a lamp of this offset pedestal construction outstanding of which is the improved balance available from offsetting one pedestal portion from the other to obtain stability in a greatly elongated leaning pedestal.

As thus described, a lamp having great utility for many purposes is provided wherein a pedestal is constructed elongated and obliquely leaning to support above the top thereof a lamp bulb usually with a shade for vertical illumination. That leaning pedestal is constructed for the most part of light transmissive material to provide lateral illumination from the pedestal per se. In preferred construction the pedestal is formed of light transmissive side paneling having greater light transmissivity than that of end panels, whereby the lateral light source has greater utility. In a modification the pedestal is divided into laterally offset vertically superimposed sections for improved balance and greater stability to provide light laterally of the pedestal from upper or lower sections, or both, as desired. The pedestal is preferably illuminated by fluorescent tubes preferably mounted inclined therein whereby to provide one or more light sources elongated substantially the length of the leaning pedestal.

Certain modifications will occur to those skilled in the art, and accordingly it is intended that the description herein given be regarded as illustrative and not limiting, except as defined in the claims appended hereto.

I claim:

1. A lamp comprising a base, a housing comprising an elongated truncated substantially pyramidal body having four sides, at least two of which comprise substantially flat surfaced light transmissive panels, said housing being mounted to said base to extend upwardly therefrom at a substantial angle of inclination from the vertical, at least one elongated fluorescent tube mounted within said housing substantially parallel to its angle of inclination whereby to provide large fluorescent lateral surface area illumination through the said light transmissive side panels of said substantially pyramidal housing, a second source of illumination mounted above and supported by said housing and bracketing means mounted to an inclined side stably securing said housing to the base in its inclined position, said bracketing means comprising a vertical member extending from the base to a point below about the center of the vertical height of said housing.

2. A lamp comprising a base, a light transmissive housing comprising an elongated truncated substantially pyramidal body mounted invertedly to said base to pyramidally slant from a smaller horizontal portion upon said base to a wider housing portion upwardly therefrom, with said housing leaning upwardly from said base at a substantial angle of inclination from the vertical, said housing being formed of substantially flat light transmissive side panels, at least one elongated fluorescent light mounted in said housing substantially parallel to said angle of inclination of said housing whereby to radiate fluorescent light from large flat surface areas of said light transmissive side panels laterally of said housing, a second source of illumination supported by and secured above said housing and a bracketing member securing said housing in inclined position to said base.

3. A lamp comprising a base forming a stable support for said lamp, a pedestal extending obliquely upward from said base, a source of illumination supported by said pedestal above its upper end, several sources of illumination supported at intermediate heights of said pedestal, each intermediate height source of illumination comprising an elongated fluorescent light extending substantially parallel to said pedestal, a substantially pyramidal shaped light transmissive housing surrounding each fluorescent light,

each said housing being formed of substantially plane surfaced light transmissive panels whereby to provide large lateral fluorescent illumination from said large substantially flat surfaces areas of said housing panels.

4. A lamp comprising a base forming a stable support for said lamp, a pedestal extending obliquely upward from said base, a source of illumination supported by said pedestal above its upper end, two sources of illumination supported at successively disposed intermediate heights of said pedestal, each said intermediate light source consisting of an elongated fluorescent light mounted substantially parallel to the inclined pedestal, each on an opposite side of said pedestal in the plane of inclination thereof, a substantially light transmissive housing surrounding each fluorescent light, each said housing being formed of substantially plane surfaced light transmissive panels whereby to provide large lateral fluorescent illumination from said large flat surfaced areas of said housing panels.

5. A lamp comprising a base, a hollow rectangular light transmissive pedestal mounted on said base having at least two of its opposite sides extending upward from the base at an angle substantially inclined to the vertical whereby to impart a substantially pyramidal shape to said pedestal, said housing being formed at least in part of substantially flat light transmissive panels to provide large lateral surface area illumination, a second substantially pyramidal shaped rectangular housing mounted above said first housing and offset laterally therefrom, said second housing similarly formed of substantially flat

surfaced light transmissive paneling, an elongated fluorescent light mounted in each housing at substantially the angle of inclination of each, and an additional source of illumination supported by and above the uppermost housing.

5. ing.
